(57) **CLAIM**

The ornamental design for a bear-shaped clock light, as shown and described.

DESCRIPTION

FIG. 1 is a front elevational view of a bear-shaped clock light showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof; and,

FIG. 8 is a top, rear and right side perspective view thereof. The broken lines in the drawings illustrate portions of the bear-shaped clock light which form no part of the claimed design.

The diagonal lines in the drawings represent reflective surfaces.
